CLAIM

The ornamental design for a suitcase, as shown and described.

DESCRIPTION

FIG. 1 is a perspective front right view of a suitcase showing our new design;

FIG. 2 is a perspective rear left view thereof;

FIG. 3 is a right side view thereof;

FIG. 4 is a left side view thereof; and,

FIG. 5 is a top view thereof.

The broken lines show a portion of the suitcase which form no part of the claimed design.
